12 Claims. (Cl. 242—65)

This invention relates to drum winding machines, and more particularly to apparatus for achieving and maintaining proper contact pressure between the surface of the driven winding drum and the outer convolution of web which is being wound into a bundle on a core as a result of bearing against the drum.

It is a general object of the present invention to provide a new and improved apparatus or "inching" mechanism for maintaining requisite contact pressure between the outer convolution of a web being wound on a core and the surface of a friction drum imparting winding drive thereto.

More particularly it is an object of the invention to provide for driving the travelling bearings, which support the core on which web is being wound by contact with the friction drum, by means of a reversible electric motor with provision being made for determining changes in the contact pressure between the bundle of wound web and the drum surface for controlling the direction of operation of the motor and the consequent advance or withdrawal of the winding core from the drum.

One of the important objects of the invention resides in the provision of riders arranged to engage supporting means for the winding core when positioned above the winding drum to increase the pressure between the web being wound thereon and the surface of the drum during the initial winding stages and to act as detecting means for determining the need for movement of the core to change the pressure exerted between the web thereon and the drum surface whereby a wound bundle of web with substantially uniform tension through the convolutions is achieved.

Another important object of the invention consists in mechanism for moving the bundle core beneath the riders from a starting position substantially directly above the axis of the drum progressively farther from the axis and displaced from the vertical therethrough until the riders are no longer effective, whereupon the drive tends to continually urge the partially wound core toward contact with the drum, means being provided in the drive system permitting slippage which automatically compensates for the increase in size of the bundle being wound.

One of the important features of the invention resides in the use of reversible reduction gearing between the apparatus for moving the travelling bearings and the winding core and slipping clutch mechanism driven by the motor, whereby travel movement of the core resulting from the pressure of web accretion may be effected reversely of the motor urge without difficulty.

Other and further objects and features of the invention will be more apparent to those skilled in the art upon a consideration of the accompanying drawings and following specification, wherein is disclosed a single exemplary embodiment of the invention, with the understanding that such changes may be made therein as fall

2

within the scope of the appended claims without departing from the spirit of the invention.

In said drawings:

Fig. 1 is a side elevation of a drum winding machine to which the present invention is applied, parts of one side frame being broken away to illustrate details of the core bearing travelling carriages;

Fig. 2 is a side elevation of the associated motor, clutch, and reduction gear assembly for driving the core carriage transfer chains; and

Fig. 3 is a partial section on the plane of line 3—3 of Fig. 1, showing the rider on the far side of the machine with its combined bundle pressure detecting means and motor reversing switch.

For many years it has been a recognized practice in winding webs of paper, fabric, plastics and the like onto a core to engage the web forming the outer convolution of the bundle with the friction surface of a constantly driven winding drum. The weight of the core and its accruing web is relied on to provide adequate peripheral contact with the drum to achieve the winding, but since the weight of the core plus its web continuously increases, there is inadequate weight and diameter to produce sufficient winding pressure to achieve a tight web at the beginning, while as the winding proceeds and more layers are added the bundle increases in diameter and weight, and if the whole weight is carried by the winding drum the increase in pressure causes the web to be more tightly wound than desired, the outer layers constricting the more loosely wound inner layers with increasing progression until the inner layers are crinkled or crushed, often spoiling them for further use.

In accordance with Patent No. 2,581,242, granted to Charles A. Dickhaut January 2, 1952, this difficulty is overcome by providing additional weight, which may be controllable in value, to augment that of the core and initial turns of the web during the early stages of the winding operation. That patent also provides means for moving the winding bundle tangentially away from its initial position directly above the axis of the drum and for maintaining a substantially uniform pressure between the surface convolution and the drum after the bundle reaches a considerable size.

The present invention contemplates an improvement on the apparatus illustrated in the above patent, eliminating complex apparatus requiring the use of compressed air and the like for its operation and substituting therefor a wholly electric drive system with electric control means.

Since the basic drum winding machine does not differ materially from that illustrated in the patent referred to above, only a brief description of the machine and its operation is deemed necessary here. The machine is primarily built up between two reinforced side plates 10 secured to a spacing base and providing support for the various parts and carrying the bearings for the drum and the necessary rotatable shafts and the like. The principal component between the said plates is the horizontally disposed drum 12 of large diameter arranged to be driven as shown by the arrow at a constant speed by any suitable mechanism, not shown, forming no part of the present invention. The web W coming from any source, such as a paper making or converting machine, passes under a guide roll 14 journaled between the side plates and then over a secondary roll which may be a spreader or the like at 15 and finally into contact with the surface of the drum. The web is to be wound on a suitable core or tube of wood, paper or other desired material and several turns are manually put about a core, not shown, which is mounted on a shaft 17 journaled in bearings 18 carried in blocks supported in

travelling carriages 19, one at each end of the shaft. As best seen in Figs. 1 and 3, the carriages are adapted to run on their respective tracks 21, one formed on or carried by each side plate of the machine. Such tracks are substantially straight and inclined slightly upwardly from the starting position shown in Fig. 1 slightly to the left of a vertical through the drum axis. They serve to support and guide the carriages as they are slowly advanced toward the right, as the web bundle grows, by a mechanism now about to be described. Each carriage track as seen in Fig. 3 has laterally spaced runners 22 defining a channel 23 in which the carriage advancing chain 24 travels. This chain is seen best in Fig. 1 where the one side plate 10 has been broken away to expose it. The chain is provided with laterally spaced side links connected by cross pins 25 which ride on the center rib 26 in the channel 23.

Each carriage is provided with a longitudinal series of teeth 28 depending on its center line between the track engaging surfaces 27 and reaching almost to the rib 26 whereby the pins 25 in the chain engage between the teeth for driving the carriage as the chain is moved.

As seen at the right end of Fig. 1, where several carriages are positioned, the one to the left being presumed to contain a completely wound bundle, the track extends beyond the chains and levels off at 29 where it is equipped with an end stop 30. The chains, however, are guided by arcuate surfaces and travel downwardly in the vertical reaches 31, thereafter following suitable curved guides such as 32 until they pass about the driving sprocket 33 and extend upward to the track. The pair of sprockets for the two chains, one for each side of the machine, are secured to a jack shaft J, journalled as shown in plates 34 adjustably attached adjacent the peripheries of suitable openings in the side frames and equipped with adjusting screws and lock nuts for controlling the tension of the chains. At the remote side of the machine as viewed in Fig. 1 the jack shaft extends beyond its bearing and is fitted with a sprocket 36 for driving by mechanism about to be described.

Power for driving the chains is taken from a suitable motor M preferably of the three phase type, capable of instantaneous reversal in a known manner. Through gearing incorporated in housing G forming an extension of the motor shell the speed of the motor is materially reduced. A magnetic brake (not shown) is incorporated in the motor in the customary manner of many commercial motors to increase the rapidity of reversal but forms no particular part of the invention. The shaft from the reducing gearing passes through the armature shaft and carries on its outer end a sprocket wheel 40.

The motor unit just described is supported above a flat base 41 for the whole drive assembly by means of an inverted U-shaped frame structure 42 to the top of which the base of the motor is bolted, as shown. Partially housed beneath the frame 42 is the miter gear speed reduction unit 43 having a transverse output shaft 44 mounting a sprocket 45 from which drive chain 46 extends to the sprocket 36, on the jack shaft J of the winding machine, for driving the chains. The longitudinally directed, horizontal drive shaft 47 of the miter gear unit 43 is coupled by flexible coupling 48 beneath the frame 42, to a clutch unit C supported between elevated bearings 50 and 51.

The clutch is of the multiple disc friction type and comprises a driven hub 53 slidably but non-rotatably secured by key 54 to shaft 55 which passes through and is journalled in bearing 51 with its outer and secured to the left hub of the flexible coupling 48 for driving the miter gear unit. The driven hub 53 is provided with an integral radial plate and a pair of movable plates 58 slidably on the reduced right extention of the hub and prevented from rotating in respect thereto by means of a key or spline. These plates, reduced in thickness for

a major portion of their outer area, are interleaved between metal annuli 59 and the driving plate 60 secured to flange 61, as shown. A plurality of pins 62 extend normal from the plate 60 near its periphery and engage in notches in the edges of the annular rings 59 so that they are constrained to rotate with plate 60 but may slide in respect thereto. Interleaved between the respective driving annuli and driven plates are the annuli of friction material radially positioned by bearing on the shoulders of the driven plates, as clearly illustrated.

The flange 61 has a hub member 63 journalled to rotate on shaft 55 and thrusting against the side of bearing 51. Drivingly attached to this hub is the sprocket 64 in alignment with motor driven sprocket 40 and adjustable idler sprocket 65 whereby a chain 66 over the three serves to drive the driving elements of the clutch at such speed as determined by the radius of diameters of sprockets 40 and 64.

The clutch is completed by extending its shaft 55 into the externally threaded sleeve 68 which journals its far end and maintains the clutch parts in alignment. The sleeve is threaded into the block 50 and provided with hand wheel 69 for adjustment longitudinally of shaft 55. Between the shoulder 70 on this hand wheel and the thrust bearing 71 arranged against the hub 53 is compressed a helical clutch spring 75. Adjustment of the hand wheel 69 changes the compression of the springs and through the sliding of hub 53 over shaft 55 determines the consequent compression of the clutch friction rings to regulate the slipping resistance of the clutch. The drive is thus from motor M to clutch driving plates and from them to the clutch driven plates, back through shaft 55, flexible coupling 48, shaft 47, miter gear unit 43, chain 46 and the sprocket of the jack shaft J, for driving the carriage advancing chains.

As described in the Dickhaut patent the carriage on each track is adapted to run beneath a rider 80 comprising at T-like device having a track 81 on the under surface of the head adapted to bear on the runners 82 on the tops of the carriages. As seen in Fig. 3, this track 81 is secured on a casting 84 whose leg 84' extends into a socket 85 on the side frame in which it is slidably guided normal to the surface of track 21. The load provided by the riders may be adjustable to provide the necessary pressure on top of the carriages during the initial winding operation, or it may be augmented by springs or the like, adjustable if desired, to insure proper winding during the early stages of putting the web on the core.

In the operation of the apparatus several turns of the web material are wound by hand onto a core, which is then placed on its shaft which is mounted in bearings 18 in a pair of carriages 19 on opposite sides of the machine while these carriages are on an elevated temporary track 55 to the left of the position of the one shown beneath the rider, where they are held out of engagement with the chain. They are then lowered or advanced to the right to engage the chains, which are driven toward the right by motor M under the sole control of a manual switch or button. This movement tends to bring the surface of the outer convolution of web on the core into engagement with the surface of the drum in advance of a radius through the drum axis normal to the track whereby the friction between the web on the core and the surface 65 of the drum starts to rotate the core. During this initial winding movement the carriages move farther beneath the riders 80 and as the core axis approaches said radius, the weight of the now lifted riders augments that of the core, its shaft, the bearings and their blocks slidably mounted between the forks of the carriages and arranged to support the runners 82. The web is now wound by the friction of the drum surface with the embryo bundle supported by the drum.

As shown in Fig. 3 the vertical sliding portion 84' of one rider is provided with a lateral bracket 88 through

which a screw 89 passes and is adapted to be secured by a lock nut. The lower end of this screw is in alignment with the operating button 90 of a single pole, double throw switch 91 of the conventional reversing type. This switch is connected, through proper electrical apparatus forming no part of the present invention, with the motor M and a source of power in such a manner that pressure of the screw on the switch button connects the motor to drive the top reaches of the chains 24 to the left and release of the button causes movement to the right. The reversing switch 91 is in control only whenever the manual button previously referred to and a manual reverse button are both released.

As the bundle begins to grow in diameter from the added convolutions of web the bearing blocks slide upwardly in the carriages 19 lifting the runners 82 and the riders which are resting on them and imparting their load to the core until the screw 89 is lifted from the button on the reverse switch, moving the carriages to the right and tending to separate the bundle from the drum. This switch thus acts as a detector to determine when too much pressure exists between the bundle and the driving drum. As the motor reverses it starts to drive the chains so that their upper travel slowly to the right as seen in Fig. 1, moving the carriages with it and tending to separate the surface of the bundle from the surface of the winding drum, but before this can happen the riders drop and the motor is reversed again, now tending to urge the bundle against the drum. This sort of operation continues alternately moving the growing bundle away and urging it against the drum to maintain a substantially uniform pressure contact between the winding web and the friction drum, the chains moving the carriages along a tangent path away from the drum surface as the bundle grows in diameter until the carriages pass from beneath the riders. The riders are sized so that they become inactive before the bundle grows very large since its weight alone plus pressure from the motor urging the bundle to the left is sufficient to obtain proper winding. As the carriages move from beneath the riders, they, having nothing to lift them, move to their lowermost positions and the switch 91 is closed in a direction to urge the carriages leftward toward the drum, insuring adequate contact for winding but advance of the carriages and the bundle is prevented by engagement of the surface of the bundle with the drum so that the clutch C begins to slip. As the bundle continues to increase in diameter movement of the carriages to the right is caused by the action of the growing bundle and thus their travel is contrary to that urged upon them by the motor M and slippage of the clutch and reversibility of the gearing in miter gear unit 43 permits this result to be achieved. The setting of the clutch in accordance with the manipulation of the hand wheel 69 and the consequent tension of the spring determines the amount of pressure existing between the bundle and the surface of the winding drum and can be regulated by the operator to suit the circumstances.

The bundle having achieved its desired size, the operator may take over the control of the movement of the carriages by the control buttons, which in their use disable the control by switch 91 to move the bundle from the position of the full line carriage at the right to a position on the horizontal portion 29 on the track as shown by the dotted line carriage where the carriages are beyond the influence of the chains and stop with the bundle positioned to be moved from the machine by any suitable device for the purpose.

Thus the objects of the invention are achieved by simple mechanism which is wholly automatic in action after the winding of the bundle has been started.

I claim:

1. In a web winding machine having a constantly driven friction drum over which the web passes, a core on which the web is wound into a bundle by peripheral contact thereof with said drum, movably mounted bearings in

75

which said core is journaled, means for providing an initial pressure on said bearings in addition to the weight of the core and initially-wound web thereon during the early part of the bundle winding operation to provide the necessary nip between the periphery of the drum and the periphery of the initially-wound web and weight supporting means separate from said bearings and cooperating therewith for at times supporting at least a portion of the weight of the core and web wound thereon; the improvement comprising means for slowly moving said bearings selectively along said weight supporting means away from or toward a position substantially directly above the drum axis including a chain, an electric motor for driving said chain, means responsive to slight bundle lift by said drum due to increase in diameter of said bundle to actuate said motor in a direction to move said bearings "away" and means responsive to excessive lowering of the bundle from partial support on the said drum to actuate the motor in the opposite direction.

2. The machine as defined in claim 1 in which a clutch is provided between said motor and chain, and means to adjust said clutch to slip on overload.

3. The machine as defined in claim 1 in which said means responsive to bundle diameter increase becomes ineffective after completion of initial winding operation and a predetermined movement of said bearings and the means responsive to lowering remains continuously responsive to urge the bundle periphery against said drum.

4. The machine as defined in claim 3 wherein said drive motor is equipped with means whereby movement of the bundle away from the drum resultant from bundle diameter increase is effected in spite of the effort of the motor in the opposite direction.

5. The machine as defined in claim 3 wherein a slipping clutch is provided between the motor and the bearing moving means whereby the movement of the bundle core away from the drum due to bundle diameter increase is effected by slipping of the clutch against the effort of the motor.

6. The machine as defined in claim 5 in which the clutch is of the multiple plate type, spring means to exert pressure on the plates to provide driving friction and manual means to adjust compression of said spring to determine the slipping resistance of said clutch.

7. In a web winding machine having a constantly driven friction drum, a core on which the web is wound into a bundle by peripheral contact of the outer web convolution with said drum, bearings journailling said core, spaced tracks substantially horizontal and tangent to the drum, a carriage slideable on each track and each receiving one of said bearings for movement therein normal to the track surface, means movable on said machine normal to said tracks to rest on said bearings to augment core and bundle weight during the early part of the winding operation to provide adequate nip as the bundle is supported by the drum; the improvement comprising means for simultaneously moving said carriages on their tracks "from" or "toward" a position substantially above the drum axis including carriage engaging means, an electric motor for driving said last mentioned means, means responsive to lift of said weight augmenting means to actuate said motor in a direction to move the carriages "from" the drum, and means responsive to lowering of the weight augmenting means to actuate said motor in the opposite direction to move the carriages, "toward" said drum.

8. The machine as defined in claim 7 in which the direction of motor drive is controlled by a reversing switch, and means biasing said switch to actuate the motor in the "from" direction.

9. The combination of claim 8 in which the switch has an operator and means movable by lowering of one of said weight augmenting means to engage said operator to change the switch to actuate the motor in "toward" direction.

10. The machine as defined in claim 7 in which a

clutch is interposed between said motor and the carriage moving means, said clutch being manually adjustable to slip on predetermined "overloads," said weight augmenting means being sized to become ineffective as the bundle grows in size to have sufficient weight of its own by the carriages moving from beneath the last mentioned means, and reversible gear interposed between the clutch and carriage moving means.

11. In a web winding machine having a constantly driven friction drum of a diameter of the order of the bundle of web to be wound thereon, a core on which the web is wound by peripheral contact of the outer web convolution with the drum, bearings journaling said core, spaced tracks beside and in a plane substantially tangent to said drum and inclined upwardly in one direction from said drum, a carriage receiving each bearing for sliding movement therein substantially normal to said track, means for simultaneously moving said carriages on their tracks upwardly "from" or downwardly "toward" a position where the axis of the core is closest to the drum surface, core and initial bundle weight augmenting means, comprising a rider associated with and slidably upwardly in respect to each track in response to engagement by the

corresponding core bearing; the improvement comprising an electric motor for driving said carriage moving means, a reversing switch for said motor, means connecting said switch and one of said riders to actuate the motor in the "from" direction when the rider is lifted and in the "toward" direction when the rider approaches its lowermost position, a friction clutch between said motor and carriage moving means, and adjuster to select the torque at which said clutch slips and a reversible speed reducer between said clutch and said carriage moving means.

12. The machine as defined in claim 11 in which said riders are constructed to be released by movement of said carriages after the bundle achieves a predetermined diameter whereby the motor is continuously operated in a direction to urge the bundle toward the drum for winding torque, the said clutch being constructed to slip under the counter torque of the movement resulting from bundle size increase.
